(57) **CLAIM**

The ornamental design for a utility pole service cabinet, as shown and described.

DESCRIPTION

FIG. 1 is a perspective view of a service cabinet installed at the base of a utility pole;

FIG. 2 is a first side view of the service cabinet;

FIG. 3 is a top view of the service cabinet;

FIG. 4 is a front end view of the service cabinet;

FIG. 5 is a rear view of the service cabinet; and,

FIG. 6 is a second side view of the service cabinet.

The portions of the utility pole service cabinet shown in broken lines form no part of the claimed design.
